CLAIM

I claim the ornamental design for a hand-held vacuum cleaner, as shown and described.

DESCRIPTION

FIG. 1 is a perspective view of a hand-held vacuum cleaner showing my new design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines in the drawings depict portions of the hand-held vacuum cleaner that form no part of the claimed design.
